GAS-BURNER.

1,033,416.

Specification of Letters Patent.

Patented July 23, 1912.

Application filed June 3, 1911. Serial No. 631,144.

To all whom it may concern:

Be it known that we, WILLIAM W. KEMP and WILLIAM H. VAN HORN, citizens of the United States, residing at Baltimore, in the 5 State of Maryland, have invented new and useful Improvements in Gas-Burners, of which the following is a specification.

This invention relates to a gas burner of that type having a plurality of jets emanating from a single gas pipe, and designed primarily for use with "gasolene" gas, or a gas produced by mixing air with a hydro-carbon vapor. The burner is also very efficient when used with retort, producer, natural and other gases.

One object of the invention is to provide a burner of the above mentioned type with nipples of novel construction for the outflow of gas to be burned, which are peculiarly 20 adapted for use with "gasolene" gas in that they are able to sustain the flame of such gas continuously without danger of it being blown out by its own pressure, a fault common with other burners when using "gasolene" gas under pressure.

Another object of the invention is to provide a water jacket for the gas burner, through which jacket a stream of water is designed to flow when the burner is ignited, 30 for the purpose of keeping down the temperature of said burner which would, otherwise, become intensely hot and lead to more or less injury of the nipples. Furthermore, burners without the water-jacket warp or 35 bow upwardly under the intense heat, thereby causing the flame in the center of the burner to be much nearer the surface being heated than the flame at the end of the burner, giving an uneven heat. This is due 40 to uneven expansion of the burner, the flame at the top of the burner being in contact with the metal structure thereof, causes the burner to expand more on the top than on the bottom, with the result that the burner 45 bows as stated. The circulation of water through the burner overcomes this distortion and also protects the burner from reflected heat, which is very destructive.

Another advantage of this burner is that, 50 because of its peculiar construction, it will burn a much thinner gas than is ordinarily used, consuming less oxygen when placed in an inclosing chamber than the ordinary burner, and, as the gas is so thin, and contains so much air or oxygen, the combustion

can be forced and a high flame temperature attained with a very small volume of fire.

With these and other objects in view the invention consists in the novel construction, arrangement and combination of parts hereinafter described, and particularly pointed out in the claims, reference being had to the accompanying drawings, in which—

Figure 1 is an exterior view of one form of the improved burner surrounded by a water jacket. Fig. 2 is a central longitudinal sectional view of one end of the burner situated within a calender roll. Fig. 3 is a cross-sectional view on the line 3—3 of Fig. 1. Fig. 4 is a central sectional view enlarged of one of the burner nipples. Fig. 5 is a perspective view of the slotted diaphragm block which forms a part of the burner nipple. Figs. 6, 7 and 8 are views in cross section of modified forms of the burner.

Similar numerals of reference are used for the same parts in all the figures.

In the drawing, the numeral 10 designates a pipe or manifold into or through which gas may pass and flow out for ignition by way of a plurality of short nipples or burners 11, threaded thereinto and projecting from the side of said pipe. The gas pipe or manifold 10 may be straight, as represented, or of other desired or convenient form.

Each nipple 11 is preferably tapered slightly from its outer end inwardly to a shoulder 13, from which latter projects a threaded stem 14 screwed into an opening in said manifold. Each nipple has a straight bore 15 extending thereinto nearly to the line of the shoulder 13, from which point the bore continues, but is of less diameter as at 16, nearly to the end of the stem 14, through which end is made a small perforation 17 into the reduced bore 16 to admit gas from the manifold into the nipple. The bottom of the bore 15 forms a seat or stop 18 against which rests one end of a relatively thick diaphragm block 19, fitting tightly in the bore 15, and provided with a number of longitudinal slots 20, extending from the peripheral surface of said block radially or if desired, tangential to a circle concentric with the axis of the block and from end to end of the same. A small hole 21 may be made through the center of the block 19 if desired.

Gas from the manifold 10 passes into the several nipples 11, through the small open-

ings 17, and thence through the several slots 20 in the block 19 to its outer end where it is ignited. The nipple 11 extends beyond the diaphragm block 19 and forms a combustion chamber of the outer end of the bore 15 that protects the flame from extinguishment by external drafts or air currents; and because of the fact that combustion takes place within the bore 15, the flame can be delivered under a heavy blast which would be impossible were the exterior face of the diaphragm block and the outer end of the nipple in the same plane; or were the gas ignited at the end of the bore 15 instead of at the end of the diaphragm block. The openings 17 in the lower ends of the nipples are made small, their combined area being much less than the cross-sectional area of the manifold 10, the effect of which is that the gas will be introduced into each nipple under the same pressure, each tube thus consuming the same volume of gas in a given time with the result that a uniform flame and temperature throughout the entire length of the burner is obtained. Were the openings 17 large the gas would back up in the far end of the burner and cause the flame on that end to be much higher and more intense than on the supply end.

Practical demonstration has shown many advantages gained by the use of a relatively thick diaphragm provided with longitudinal grooves or kerfs instead of a thin partition made of perforated or slotted metal or wire gauze, which forms are in common use at the present time. Among the advantages may be noted the fact that by the use of a thick diaphragm the burner does not get so hot as when a thin one is used, and furthermore that a thin sheet metal or gauze diaphragm will be quickly destroyed by the heat of the flame, whereas a thick diaphragm such as shown in Fig. 5 will not be affected by the intense heat. The flame "holds" to the thick diaphragm better than to a perforated or sawed disk and is rarely blown out by the pressure of the gas. With the disk construction, however, the flame is blown out quickly and very often. The thick diaphragm furthermore, will last a long while because of its freedom from destruction by the heat of the flame.

Surrounding the manifold 10 in the construction shown, is a water jacket or casing 25, spaced a short distance from the manifold and provided with heads 26 and 27 with a water inlet and outlet 28 and 29 respectively. In the construction shown in Figs. 1 to 4, a plurality of tapering holes 60 are made through the wall of the water jacket 25 to receive the nipples 11, which are passed through said holes and screwed into the manifold when the parts are assembled. For the purpose of retaining the manifold and water jacket in proper rela-

tion to each other and form water tight joints between the nipples and the openings in the water jacket through which they pass, a plurality of screws 30 are threaded radially in the water jacket on opposite sides of the nipple and bear at their inner ends against the manifold 10. By tightening these screws the manifold and water jacket tend to separate and as the nipples are attached to the manifold they will be drawn inwardly so that the tapering outer surfaces of the nipples will be firmly seated in similarly tapered holes in the water jacket and close said openings tightly against the passage therethrough of the water in the water jacket.

Instead of making the nipples with exterior walls diverging at their outer ends away from the axis of said nipples, they may be made converging as in Fig. 6, to fit 85 similarly inclined openings in the water jacket 25^a. In this case the screws 30 bear against the under side of the manifold 10^a to force the nipples 11^a into the openings in the water jacket. Another form of nipple is shown in Fig. 7. In this instance, the nipple 11^b converges from about its center toward each end and the holes in the manifold 10^b and water jacket 25^b are made tapering to correspond with the taper on the 90 exterior of the nipple. When the screws 30 below the manifold, are turned in the proper direction said manifold is forced upwardly and causes the nipples to seat themselves in their respective openings in the manifold 100 and water jacket. The nipples may also be made as in Fig. 8, where it will be seen that the nipples 11^c are threaded into the water jacket 25^c and have their lower or inner ends converged to seat themselves in similarly shaped openings in the manifold 10^c. The screws 30 are, in this instance, also placed below the manifold to force the same upwardly to produce a tight joint between 105 itself and the nipple.

The nipples are cheap, simple and very efficient and consist of two parts only, the nipple proper 11 and the diaphragm block 19, the latter being made to fit so tightly in the bore of the nipple as to require no other 110 fastening means. The slots 20 therein are made very quickly and without trouble with a saw or other tool.

Fig. 2 shows the improved burner applied to a calender roll used in textile finishing plants and paper mills, where experience has demonstrated that the efficiency of such rolls when so heated greatly exceeds the present method of heating these rolls by steam, which cannot raise the temperature 115 of said rolls above a certain point, but with gas these rolls can be heated to and maintained at any desired temperature. Gas burners have not been used extensively for heating calender and similar rolls from 120

within the rolls, because there never yet has been a burner which could resist the intensity of the heat by which it is surrounded, and there never has been a burner, so far as known, capable of utilizing a very thin gas and make such good combustion and even heat as is necessary and desired. With the improved burner above described surrounded by a water-jacket, an intense heat can be maintained without detriment to the burner and perfectly adapted to consume a very thin gas.

It is to be distinctly understood that the diaphragm block 19 and the nipple or burner *per se* of which it forms a part, herein shown and described, is not claimed in the present application as it forms the subject matter of a separate application filed by us on the 18th day of January, 1912, Serial No. 671,907.

We claim:—

1. In a device of the kind described, a gas pipe, a jacket surrounding said gas pipe and spaced therefrom to form a receptacle for a cooling medium, a plurality of nipples each extending across said receptacle and through the jacket, their other ends connecting with the gas pipe, and means for adjusting the jacket and gas pipe relatively to each other to form fluid tight connections with the nipples.

2. In a device of the kind described, a gas pipe, a jacket surrounding said gas pipe and spaced therefrom to form a receptacle for a cooling medium, and a plurality of nipples each extending across said receptacle and through the jacket, their other ends communicating with the gas pipe, said nipples being screw-threaded to one of said parts and having tapered frictional connection to the other part.

3. In a device of the kind described, a gas pipe, a plurality of nipples projecting from said gas pipe and communicating with its interior, a water jacket surrounding the gas pipe through which jacket the outer ends of said nipples project, and means for adjusting the gas pipe and jacket relatively to form fluid tight connections with the nipples.

4. In a device of the kind described, a manifold gas pipe, a plurality of nipples screwed at their inner ends into said manifold and communicating with its interior and having tapered outer ends, a water jacket surrounding said manifold through which water jacket the outer tapered ends of said nipples project, and means for holding said nipples fluid tight in the water jacket.

5. In a device of the kind described, a

manifold gas pipe, a plurality of tapering nipples projecting therefrom and communicating with said manifold, a water jacket surrounding said manifold and provided with tapering openings in its side through which the tapering nipples project, and tightening screws threaded in said water jacket to bear at their ends against the manifold for holding the manifold and water jacket in fixed relation and the nipples fluid tight in the openings of said water jacket.

6. In a device of the kind described, a manifold gas pipe, a plurality of tapering nipples projecting therefrom and communicating with said manifold, a water jacket surrounding said manifold and provided with tapering openings in its side through which the tapering nipples project, and tightening screws extending through the water jacket on opposite sides of the nipples and bearing at their inner ends against the manifold to hold the parts in fixed relation and the nipples fluid tight in said tapered openings.

7. A nipple for gas burners comprising a body portion having tapering sides and a threaded neck, a central bore in said body, a bore of less diameter in said neck, and a small hole in the end of the nipple communicating with the smaller bore, said bore containing a relatively thick diaphragm having slots extending from its peripheral surface inwardly, fitting tightly in the larger bore and extending nearly to the top of the body portion.

8. In a device of the kind described, a manifold gas pipe, a water jacket surrounding said manifold, a plurality of nipples extending from said manifold through the water jacket and fitting tightly in openings in said manifold and water jacket, said nipples each having a bore, and a relatively thick diaphragm having a small central perforation and a plurality of slots in its peripheral surface situated in said bore below its outer end, a small inlet opening being formed at the lower end of each nipple communicating with said manifold, the combined area of the inlet openings being less than the cross-sectional area of the manifold.

In testimony whereof we have hereunto set our hands in presence of two subscribing witnesses.
